COMPRESSOR

Lewis C. Hufford and Landon R. Gray, Redondo Beach, Calif., assignors to Hufford Machine Works, Inc., Redondo Beach, Calif., a corporation of California

Application June 19, 1944, Serial No. 540,975

18 Claims. (Cl. 103—54)

Our invention relates to a compressor and more particularly to an internal combustion-hydraulic compressor.

An important object of the invention is to transmit directly to a pumping fluid the expansive force in an internal combustion engine, without the use of crank shafts, rotary pumps, gears, etc. The pressure placed upon the fluid is in turn used for useful work to drive fluid-driven mechanisms.

Another object of the invention is to provide means of the character described that will automatically produce more power when more power is needed and less power when less is needed.

A further object is to provide a system, including a streamlined pumping arrangement that directly employs the expansive force in an internal combustion engine, and utilizes a fraction of the fluid pumped thereby to operate intake, exhaust and ignition timing means for the internal combustion engine.

Our invention also has for its objects to provide such means that are positive in operation, convenient in use, easily installed in a working position and easily disconnected therefrom, economical of manufacture, relatively simple, and of general superiority and serviceability.

The invention also comprises novel details of construction and novel combinations and arrangements of parts, which will more fully appear in the course of the following description. However, the drawing merely shows and the following description merely describes one embodiment of the present invention, which is given by way of illustration or example only.

In the drawing, like reference characters designate similar parts in the several views.

Fig. 1 is a partly diagrammatic representation of a system embodying the foregoing objects, certain parts being shown in broken sectional views.

Fig. 2 is a section taken on the line 2—2 of Fig. 1.

Fig. 3 is a section taken on the line 3—3 of Fig. 1.

Fig. 4 is a section taken on the line 4—4 of Fig. 1.

Referring more in detail to the drawing, the reference number 4 designates a cylinder of an internal combustion engine having an intake pipe 5 for fuel, and an exhaust pipe 6 for spent gases of combustion. A spring biased valve 7 controls an inlet port 8 for fresh fuel. The spring 9 on the valve 7 is a light spring to permit the valve to open on the suction or downward stroke of a piston 10 in the cylinder 4.

An exhaust valve 12 controls the exhaust port 13 leading to the exhaust conduit 6. A spring 14 tends to seat the valve 12. A stem 15 of the valve 12 continues lengthwise into a relatively small cylinder 16 in which reciprocates a piston 17 mounted on the stem 15. A conduit 18 supplies pressure fluid to the cylinder 16 at a side of the piston 17 to actuate same.

It is to be understood that any type of internal combustion engine may be employed in the present system, e. g. four-cycle, two-cycle, or Diesel.

For either of the former types, a spark plug 19 may be mounted in the head 20 of the cylinder 4, or in any other suitable place. Wiring 21 is shown connecting with the spark plug 19.

The piston 10 has a ram-like neck 11 connecting at its opposite end with an enlarged head 22 providing a plunger of preferably slightly less diameter than the piston 10. The plunger head 22 has a loose, sliding fit with a comparatively short portion 23 of the wall of the cylinder 4. A chamber in which the head 22 reciprocates is shown at 24 in broken longitudinal section. The chamber 24 has a minimum length of approximately the distance from the lower side of the piston 10 to a restricting inward flange or partition 25, as they are shown in Fig. 1. A slightly restricted portion 26 at the lower end of the chamber 24 is approximately the same inside diameter as the cylindrical portion 23.

A pipe 27 connects with a fluid reservoir (not shown) for supplying fluid to the chamber 24. A valve 28 controls the flow of the fluid from the pipe 27 to a port 29 leading into the chamber 24. A fluid motor 30 operates the valve 28. A pipe 31 supplies fluid to the motor 30.

Fluid driven from the chamber 24 passes through the outlet passage 32, past a check valve 33. A spring 34 tends to move the valve 33 to a seat 35, but permits the check valve to open when fluid is driven under pressure through the passage 32 by means of the piston head 22. A discharge conduit 36 carries the fluid that is discharged under pressure from the chamber 24 through the passage 32.

It will be noted that there is a restricted annular space 37 in the cylinder 4 around the neck 11 of the plunger and between the piston 10 and the inward flange 25. A pipe 38 connects with the lower end of such space, as it is shown in Fig. 1.

The discharge conduit 36 leads to an accumulator 39 that contains a floating piston 40. There is an air compressing space 41 above the floating piston 40 and a pressure fluid space 42 below the

piston. It is believed clear without further illustration that a diaphragm may be used instead of the floating piston 40.

A conduit 43 is shown alined with the conduit 38 and also connected with the accumulator 39. The conduit 43 leads to a control valve 44, of any suitable design, operated by a lever handle 45 that has a pointer 46 registering with a graduated scale 47. A conduit 48 conveys pressure fluid from the valve 44 to a fluid motor 49, best shown in Fig. 3. From the motor 49, the pressure fluid may be carried by a conduit 50 to do any desired work, such as fluid-operated mechanism. Eventually the fluid, after its pressure has been spent, may be transmitted back to the reservoir with which the pipe 27 connects.

Journals 51, 52 and 53 rotatably support a shaft 54 that is driven by the gear motor. The shaft 54 carries three cams, 55, 56 and 57, which respectively engage heads 61, 62 and 63 of sliding valves 61, 62 and 63. Each of these sliding valves has opposed pistons, as shown at 64 and 65, joined by a reduced connecting member 66. A coil spring 67 urges the piston assembly toward the cam and to a position in which the piston 64 closes the outlet conduit of the valve. The inlet conduits to the valves 61, 62 and 63 are shown by arrows D. The outlet conduits of the valves 61, 62 and 63, are the conduits 31, 32 and 18, respectively, previously mentioned. A pipe 68 connecting with the conduit 43 has three branches 69, 70 and 71 that respectively connect with and provide inlet conduits for the valves 61, 62 and 63.

When the cams 55, 56 and 57 move the sliding valves 61, 62 and 63, to the left in Fig. 1, the piston 64 uncovers the outlet conduits, permitting flow of pressure fluid from inlet conduits to the outlet conduits past the reduced connecting member 66. When the cams are turned to release the sliding valves, the springs 67 move the valves to a closing position.

The fourth cam 72 on the shaft 54, wipes an insulating pad 73 on a movable, grounded contact support 74. A spaced contact support 75 is connected with the wiring 21 and in turn carries a contact 76 that engages a contact 77 on the support 74, when the cam 72 urges them together. When the cam 72 is turned around from the position shown, the inherent resilience of the support 74 will separate the contacts 76 and 77, breaking the circuit of the spark plug 19.

In the operation of our present system, energy provided by the expansion of ignited gases in the cylinder 4 is directly transmitted to the fluid in the chamber 24 without the intermediary of a crank shaft, gears, or other conventional means for transmitting energy from an internal combustion engine to provide pressure upon a fluid.

It is to be understood that the fluid may be of a wide variety of liquids or gases. Oil is merely suggested as an efficient fluid that may be used in our system.

The operation will be described in connection with a four-cycle engine: the fuel for the internal combustion engine is automatically drawn into the conduit 5 by suction of the piston 10 by reason of its downward stroke in the direction indicated by the two arrows A touching the top of the piston 10 in Fig. 1. The cam 56 is so arranged that it maintains the valve 62 open during the downward stroke of the piston 10. This permits fluid in the annular space 37 to pass therefrom through the conduit 38 in a direction opposite to the arrow B, through the valve 62 and by means of

the branch 70 and the conduit 68, back to the system.

On the next upper stroke of the piston 10, the fuel that has been drawn in above the piston will be compressed. Then upon ignition of the compressed fuel, near the top of the stroke of the piston 10, by the spark plug 19, the piston 10 again travels down, as shown by the arrows A, for the power stroke. The expansive force of the ignited gases in the cylinder 4 maintains the valve 7 closed on this power stroke.

During each downward stroke of the piston 10, as it is shown in Fig. 1, the valve 28 is closed against the intake of any more fluid, and the check valve 35 is opened for the discharge of fluid from the chamber 24 to the conduit 38. Each upward stroke of the piston 10 causes the closing of the valve 33. On the compression stroke of the piston 10, the valve 28 is opened for the inlet of fresh fluid from the reservoir. On the exhaust stroke of the piston 10, however, the valve 28 is kept closed, in order to produce a partial vacuum in the chamber 24. This partial vacuum causes the piston 10 to move downward for its fuel intake stroke, after the exhaust stroke is completed.

Pressure is built up in the accumulator 39 above the floating piston 40, by the inflow of pressure fluid into the accumulator chamber 42. This stored power in the accumulator runs the engine through idle stroke and is useful for smoothing out and facilitating the starting of the engine.

The pipe 68 bleeds the conduit 43 of a relatively small amount of pressure fluid for operating the exhaust, intake, ignition, and piston operating valves. During the upward strokes of the piston 10, the valve 61 is open in order to open the valve 28 for the intake of fresh fluid from the reservoir. During the intake and power strokes of the piston, the cam 55 is turned away from its engaged head 58, permitting the spring 67 in the valve 61 to move the piston assembly 64, 65, 66 to the right in Fig. 1. The conduits 31 and 32 are thereby connected. The conduit 31 connects with the reservoir that supplies fluid to the conduit 27.

Of course, the check valve 33 is closed on these upward strokes of the piston, by means of the spring 34, to prevent the retrograde movement of the pressure fluid from the line 36. During said upward strokes, the fuel intake valve 7 is closed. Then on the upward exhausting stroke of the piston, the valve 63 is opened to allow fluid pressure in the conduit 18 to open the exhaust valve 12 by means of the fluid motor 16, 17. The exhaust from the previously ignited fuel is thereby allowed to escape through the exhaust pipe 6.

During the fuel intake stroke of the piston, the valve 62 is in the position shown in Figs. 1 and 2, to-wit, connecting the conduit 38 with a pipe 80 that leads back to the reservoir. It is to be understood that said reservoir is under atmospheric pressure. Then, for the compression stroke of the piston 10 the cam turns to shut off the flow to the conduit 80 and permits flow of pressure fluid from the branch 70 through the valve 62 and through the conduit 38 to the space 37, thereby raising the piston 10. In going through the valve 62, the fluid passes around the narrow connecting member 66, since the piston 64 is at the left of the opening into the conduit 38.

On the firing stroke, the valve 62 still remains open, so that pressure fluid forced through the conduit 38 may pass through the valve 62 and

enter the pressure system. On the exhaust stroke, the valve 62 is still open, so that pressure in the system may raise the piston 10. In other words, the valve 62 connects conduits 88 and 70 at all times, except on the fuel intake stroke, when the valve 62 connects the conduit 88 with the reservoir pipe 80.

The amount of pressure fluid that goes into the motor 49 and to the work mechanism that is operated by the fluid is determined by the control valve 44.

The short cylinder portion 28 provides a pocket 82 when the head is in a raised position, as in Fig. 1. Fluid within the pocket 82 has a cushioning effect upon the upward strokes of the piston. The fluid in the pocket 82 is permitted to leak around the head 22, since the head has a loose, sliding fit with the inner face of the cylinder portion 28, whereby the head 22 in the pocket 82 acts as a dashpot.

The shaft 64 is timed to make one revolution in each complete cycle of operation of the engine. It is believed clear that one skilled in the art may so adjust the cams on the shaft that they open and permit the closing of the control valves at the required times in order to produce the foregoing operation.

When less work is required of the pressure fluid driven from the chamber 24, then the piston 10 is permitted to take a longer stroke, which saves fuel. On the other hand, if there is considerable resistance to the pressure fluid driven from the chamber 24, by reason of more work having to be done, then the piston 10 takes a shorter stroke and the internal combustion engine has more complete cycles of operation in a given period of time, in order to produce more power.

It is believed clear without further illustration that the intake, exhaust, ignition and piston control means may be actuated by electrical means (e. g., solenoids) or by mechanical means (e. g., crank shaft and cams) as well as by the hydraulic or fluid motors shown and described.

While we have illustrated and described what we now regard as the preferred embodiment of our invention, the construction is, of course, subject to modifications without departing from the spirit and scope of our invention. We, therefore, do not wish to restrict ourselves to the particular form of construction illustrated and described, but desire to avail ourselves of all modifications that may fall within the scope of the appended claims.

Having thus described our invention, what we claim and desire to secure by Letters Patent is:

1. In a compressor, a cylinder having fuel intake and exhaust means, a piston in the cylinder arranged to be actuated by ignition of fuel in the cylinder, means providing a fluid chamber having fluid inlet and discharge means, the piston being mounted to operate in said chamber to draw fluid into the chamber through said inlet means and to drive fluid therefrom through said discharge means when actuated by ignited gases of combustion in said cylinder, and a motor operable by a portion of the fluid driven from said chamber to control said inlet means.

2. In a compressor, a cylinder, a reciprocating piston in the cylinder, the cylinder having fuel intake and exhaust means at one side of the piston and having fluid inlet and discharge means at the opposite side of the piston, to draw fluid into the cylinder through said inlet means at one stroke of the piston and to drive the fluid from the cylinder through said discharge means when fuel is ignited at the opposite side of the piston,

and fluid pressure operated timing means controlling the exhaust means.

3. In a compressor, an elongated cylinder, a reciprocating piston in the cylinder, the cylinder having fuel intake and exhaust means at one side of the piston and having fluid inlet and discharge means at the opposite side of the piston arranged to draw fluid into the cylinder at said inlet means on the return stroke of the piston, valve means connected to close said inlet on the power stroke of the piston, the discharge means being arranged to convey fluid under pressure from the cylinder on said power stroke, and timing means connected to close the exhaust means and said valve means on the power strokes of the piston.

4. In a compressor, a cylinder, a floating piston and plunger arranged back to back in unitary structure within the cylinder, the cylinder having fuel intake and exhaust means at one side of the piston and having fluid intake and discharge means at the opposite side of the plunger, a valve to control said exhaust means, valves arranged to control the fluid intake and discharge means, and fluid pressure operated timing mechanism connected to operate said exhaust and fluid intake valves in the operation of the apparatus.

5. In a compressor, a cylinder having an apertured partition therein, a floating piston and plunger arranged back to back in unitary structure within the cylinder, the piston and plunger being connected by a reduced neck portion arranged to slide within the aperture in the partition with the piston and plunger at the opposite sides of the partition, the cylinder having fuel intake and exhaust means at one side of the piston and having fluid intake and discharge means at the opposite side of plunger, conduit means connected to supply fluid pressure between the partition and the piston to actuate the latter, valve means connected to supply to said conduit means a fraction of the fluid emitted by the discharge means, and timing mechanism connected to maintain said valve open to supply pressure fluid to actuate the piston for its compression stroke.

6. In a compressor, a cylinder, a floating piston in the cylinder, the cylinder having fuel intake, ignition and exhaust means at one side of the piston and having fluid intake and discharge means at the opposite side of the piston, an electric circuit for the ignition means including relatively movable contacts, and mechanism controlled by the discharge of fluid from the cylinder arranged to close the contacts and time the ignition of fuel in the operation of the apparatus.

7. In a compressor, a cylinder, a floating piston in the cylinder, the cylinder having fuel intake and exhaust means at one side of the piston and having fluid discharge means at the opposite side of the piston, conduit means connected to supply a fraction of the fluid emitted by the discharge means under the piston to actuate same for its return strokes, a valve controlling the flow through the conduit, and mechanism controlled by the discharge of fluid from the cylinder connected to time the operation of the valve.

8. In a compressor, a cylinder, a reciprocating piston in the cylinder, the cylinder having fuel intake and exhaust means at one side of the piston and having fluid discharge means at the opposite side of the piston, a fluid motor con-

nected to control the exhaust means, the fluid motor in turn being connected to be operated by a fraction of the fluid emitted by the discharge means, a valve connected to control the fluid motor, and mechanism controlled by the discharge of fluid from the cylinder connected to time the operation of the valve.

9. In a compressor, a cylinder, a floating piston in the cylinder, the cylinder having fuel intake and exhaust means at one side of the piston and having fluid inlet and discharge means at the opposite side of the piston, a fluid motor connected to control the fluid inlet means, the fluid motor in turn being connected to be operated by a fraction of the fluid emitted by the discharge means, a valve connected to control the fluid motor, and mechanism controlled by the discharge of fluid from the cylinder connected to time the operation of the valve.

10. In a compressor, a cylinder, a floating piston in the cylinder, the cylinder having fuel intake and exhaust means at one side of the piston and having fluid inlet and discharge means at the opposite side of the piston, an accumulator connected with the discharge means arranged to store pressure therefrom to aid in subsequent operation, and mechanism connected to control the exhaust and fluid inlet by the discharge of fluid from the cylinder, under the influence of the accumulator.

11. In a compressor, a cylinder, a reciprocating piston in the cylinder, the cylinder having fuel intake and exhaust means at one side of the piston and having fluid inlet and discharge means at the opposite side of the piston, a fluid motor connected to control the exhaust means, the fluid motor in turn being connected to be operated by a fraction of the fluid emitted by the discharge means, a valve connected to control the fluid motor, and fluid motor means connected to be driven by other of the fluid discharged by said discharge means and in turn connected to time the operation of said valve.

12. In a compressor, a cylinder, a reciprocating piston in the cylinder, the cylinder having fuel intake and exhaust means at one side of the piston and having fluid inlet and discharge means at the opposite side of the piston, a fluid motor connected to control the fluid inlet means, the fluid motor in turn being connected to be operated by a fraction of the fluid emitted by the discharge means, a valve connected to control the fluid motor, and fluid motor means connected to be driven by other of the fluid discharged by said discharge means and in turn connected to time the operation of said valve.

13. In a compressor, a cylinder, a reciprocating piston in the cylinder, the cylinder having fuel intake and exhaust means at one side of the piston and having fluid inlet and discharge means at the opposite side of the piston, a fluid motor connected to control the exhaust means, the fluid motor in turn being connected to be operated by a fraction of the fluid emitted by the discharge means, a sliding, spring-biased valve connected to control the fluid motor, cam means arranged to slide the valve in one direction against the action of said spring and the cam means being arranged to be moved to a position permitting the spring to slide the valve to the opposite position, to op-

erate the valve to and from a given position, and fluid motor means connected to be driven by other of the fluid discharged by said discharge means and in turn connected to time the operation of said cam means.

14. In a compressor, a cylinder, a reciprocating piston in the cylinder, the cylinder having fuel intake and exhaust means at one side of the piston and having fluid inlet and discharge means at the opposite side of the piston, a fluid motor connected to control the fluid inlet means, the fluid motor in turn being connected to be operated by a fraction of the fluid emitted by the discharge means, a sliding, spring-biased valve connected to control the fluid motor, cam means arranged to slide the valve in one direction against the action of said spring and the cam means being arranged to be moved to a position permitting the spring to slide the valve to the opposite position, to operate the valve to and from a given position, and fluid motor means connected to be driven by other of the fluid discharged by said discharge means and in turn connected to time the operation of said cam means.

15. In a compressor, a cylinder, a reciprocating piston therein, the cylinder having intake and exhaust means at one side of the piston and having fluid inlet and discharge means at the opposite side of the piston, the discharge means being adapted to convey fluid under pressure from the cylinder on the power stroke of the piston, and means to utilize a fraction of the pressure fluid to actuate the piston for its return stroke, thereby to draw fluid into the cylinder through said inlet means.

16. In a compressor, a cylinder, a floating piston and plunger arranged in spaced relation in unitary structure within the cylinder, the cylinder having fuel intake and exhaust means at one side of the piston and having fluid intake and discharge means at the opposite side of the plunger to draw fluid into the cylinder through said inlet on the return stroke of the piston, a valve to close said inlet on the power stroke of the piston, and means to supply to the space between said piston and plunger a fraction of the fluid discharged from the cylinder by the power stroke of the piston to effect the return stroke of said piston.

17. In a compressor, a cylinder, a floating piston in the cylinder, the cylinder having fuel intake and exhaust means at one side of the piston and having fluid discharge means at the opposite side of the piston, means to supply a portion of the fluid forced through said discharge means to said cylinder to actuate the same for its return stroke, and means to control said supply means.

18. In a compressor, a cylinder, a floating piston in said cylinder, the cylinder having fuel intake and exhaust means at one side of the piston and having fluid discharge means at the opposite side of said piston, means to supply a portion of the fluid forced through said discharge means to said cylinder to actuate the piston for its return stroke, a valve to control said supply means, and means to operate said valve.

LEWIS C. HUFFORD.
